UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

DESIGN FOR AN ELECTRIC-LIGHT CLUSTER.

No. 39,057.

Specification for Design.

Patented Feb. 4, 1908.

Application filed December 24, 1906. Serial No. 349,364. Term of patent 14 years.

To all whom it may concern:

Be it known that I, REUBEN B. BENJAMIN, a citizen of the United States, residing at Chicago, in the county of Cook and State of Illinois, have invented a new, original, and ornamental Design for Electric-Light Clusters, of which the following is a specification, reference being had to the accompanying drawing, forming part thereof.

Figure 1 of the drawings is a perspective

view of my design for electric light cluster. Fig. 2 is a bottom plan view of my electric light cluster.

I claim:

The ornamental design for electric-light cluster, as shown.

REUBEN B. BENJAMIN.
